UNITED STATES PATENT OFFICE.

ADELBERT M. TOWLE, OF AUGUSTA, MAINE.

SHOE POLISHER AND GUARD.

1,258,828.

Specification of Letters Patent. Patented Mar. 12, 1918.

Application filed March 24, 1917. Serial No. 157,190.

To all whom it may concern:

Be it known that I, ADELBERT M. TOWLE, a citizen of the United States of America, residing at Augusta, in the county of Kennebec and State of Maine, have invented certain new and useful Improvements in Shoe Polishers and Guards, of which the following is a specification.

This invention relates to certain improvements in shoe polishers and has relation more particularly to a device of this general character especially designed and adapted for use in the polishing up of a shoe in the last stages of manufacture and particularly wherein the welt or the stitching is of a color different from that of the upper of the shoe; and it is an object of the invention to provide a novel and improved device of this general character including a holder for a swab or sponge and wherein said holder serves as a guard to prevent the polish or dressing when applied to the shoe upper by the swab or sponge from smirching or soiling the shoe welt or the stitches disposed through the welt.

The invention also has for an object to provide a novel and improved device of this general character which permits the "dresser" or "treer" to polish up a shoe with greater expedition than is possible by the methods now generally employed.

The invention consists in the details of construction and in the combination and arrangement of the several parts of my improved polisher whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein

Figure 1 is a view in top plan of a shoe polisher constructed in accordance with an embodiment of my invention;

Fig. 2 is a view in side elevation of my improved device with the swab or sponge omitted;

Fig. 3 is a fragmentary view in plan of the free extremity of the returned portion of the plate as herein embodied; and Fig. 4 is a horizontal longitudinal sectional view

taken through the device as herein embodied with certain of the parts indicated by dotted lines.

As herein disclosed, my improved polisher comprises the flat elongated metallic plate P having one end portion angularly disposed in a direction transversely of the plate P, as at 1, with a margin of said angularly disposed portion disposed on a predetermined curvature, as indicated at 2. The opposite end portion of the plate P is returned, as indicated at 3.

The angular portion 1 of the plate P is provided with the openings 4 arranged in an oblique plane relative to the longitudinal axis of the portion 1.

Threaded through the openings 4 is a length of wire 5 or the like having its outer end portions angularly disposed, as indicated at 6, to afford heads so that when the outer or free end portions of the wire 5 are seated within the open slots 7 produced in the free extremity of the returned portion 3, the same will be effectively locked therewith. This locking action is further enhanced in view of the fact that the returned portion 3 possesses a certain degree of inherent resiliency.

As disclosed in the accompanying drawings, it is preferred that the slots 7 be arranged in convergence with their closed ends forwardly directed. It has also been found of advantage to provide the inner or closed end portions of the slots 7 with the forwardly directed notches 8 in which the extremities of the wire 5 are adapted to be seated in order to further facilitate the locking of said free end portions of the wire with the returned portion 3 of the plate P.

S denotes a swab of any desired material but preferably of sponge and which is held to the plate P through the medium of the wire 5, said swab being disposed between the strands 9 of the wire 5 when the free end portions of said wire are in locked engagement with the returned portion 3 of the plate P, as has hereinbefore been set forth.

In operation the dresser grasps the polisher with his or her four fingers contacting with the plate P with the forefinger adjacent the outer end of the angular portion 1 and with the thumb engaging the swab at a point remote from the portion 1. The operator inserts the left hand within the shoe to be dressed with the thumb at the

heel portion thereof and the fingers fanned within the toe portion of the shoe. With the shoe in an inverted position the polisher is drawn therearound with the angular portion 1 extending between the welt and the upper of the shoe. By this arrangement it will be perceived that the portion 1 effectively serves to prevent the polish or other dressing carried by the swab from smirching or soiling the welt of the shoe or the stitches passing therethrough. It is preferred that the guard be engaged between the welt and upper of the shoe adjacent the back seam and then passing the polisher entirely around the shoe. It will be understood however that after the portion of the upper adjacent the welt has been dressed the body portion of the swab or sponge may be employed for applying polish or dressing to the entire portion of the upper.

As illustrated in the accompanying drawings, the major portion of the plate P is shown as disposed along the right side of the swab or sponge. In the event, however, that it is desired to employ my polisher in connection with a shoe supported by a conventional type of "tree" as is sometimes generally employed, it is to be understood that the major portion of the plate P is to be positioned along the left side of the swab or sponge.

In practice the end portion of the plate P as defined by the curved margin 2 serves as the working portion of the device, while the remaining portion of the plate P together with the strands 9 serve to maintain the swab S compactly in applied position.

From the foregoing description, it is thought to be obvious that a polisher constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement

and formation of the several parts herein shown in carrying out my invention in practice, except as hereinafter claimed.

I claim:

1. A device of the character described comprising an elongated plate having one end portion provided with a return bend, members engaged with the opposite end portion of the plate and operatively engaged with the bent portion of the plate, and a swab resting upon the plate and extending between the members.

2. A device of the character described comprising an elongated plate having one end portion provided with a return bend, members engaged with the opposite end portion of the plate and operatively engaged with the bent portion of the plate, and a swab resting upon the plate and extending between the members, the connection between the members and the returned portion of the plate being detachable.

3. A device of the character described comprising an elongated plate having one end portion provided with a return bend, the extremity of said bent portion being provided with slots, members operatively engaged with the opposite end portion of the plate and terminating in heads, the portions of the members provided with the heads being insertible within the slots of the bent portion of the plate, and a swab disposed along the plate and between the members when said members are operatively engaged with the bent portion of the plate.

4. A device of the character described comprising an elongated flat plate having one end portion angularly disposed in a direction transversely of the plate, a margin of said angularly disposed portion being arranged on a predetermined curvature, a swab co-acting with the plate, and means for holding the swab in applied position relative to the plate.

In testimony whereof I affix my signature in the presence of two witnesses.

ADELBERT M. TOWLE.
